(57) **CLAIM**

The ornamental design for a window box, as shown and described.

DESCRIPTION

FIG. 1 is a perspective view of our new design for a window box;

FIG. 2 is a top plan view of the window box of FIG. 1; FIG. 3 is a front elevation view of the window box of FIG. 1;

FIG. 4 is a right end view of the window box of FIG. 1; FIG. 5 is a top plan view of an alternate embodiment of our new design for a window box; and, FIG. 6 is a front elevation view for the window box of FIG. 5.

The left end elevation view of the window box of FIG. 1 is a mirror image of FIG. 4.
